UNITED STATES PATENT OFFICE

ALBERT A. LONGAKER, OF TRENTON, NEW JERSEY

GUIDING MEANS FOR PARACHUTES

Application filed September 17, 1930. Serial No. 482,393.

My invention relates to parachute mechanism with particular reference to a means for guiding the direction of the parachute descent.

5 A purpose of my invention is to impel a descending parachute laterally by the reaction of laterally discharging air, using the weight and movement of the descending structure to impel the air and a regulation of the direction of air discharge to steer the parachute laterally during its descent.

10 A further purpose is to place an angularly adjustable air discharge spout above and on the body of the parachute, preferably on a light metal central terminal plate of the shrouds, passing air from beneath the parachute up through the spout to an angularly adjustable lateral discharge, changing the angle of discharge to effect a lateral steering of the descent.

15 Further purposes will appear in the specification and in the claims.

I have elected to show one only of the many forms of my invention, selecting however a 20 form that is practical and efficient in operation and which well illustrates the principles involved.

25 Figure 1 is a fragmentary elevation illustrating an opened chute with equipment embodying one form of my invention.

Figure 2 is a fragmentary top plan view of the structure shown in Figure 1.

Figure 3 is a fragmentary side elevation of Figures 1 and 2.

30 Figure 4 is an enlarged fragmentary section taken in the plane of the paper of Figure 3.

Figure 5 is an enlarged fragment of Figure 4.

35 Like numerals refer to like parts in all figures.

40 Describing in illustration and not in limitation and referring to the drawings:—

In the conventional illustration the fabric body 6 of the parachute extends outwardly 45 from a plate 7 that forms a terminal for both the fabric body and also for the shrouds 8 which pass outwardly over the fabric to the outer edge thereof at 9 and thence converge diagonally downwardly at 10 to the support 50 of the user.

I use the central terminal plate 7 also as a bearing support for an angularly adjustable lateral air discharge spout 11 providing the plate with an upwardly flanged suitable circular opening at 12 which receives a downwardly directed flange 13 of a turn base mount 14 that forms the inlet terminal of the discharge spout. 55

The discharge spout includes the light metal mount 14 at the spout inlet, a ring or 60 nozzle 15 at the spout outlet, a collapsible accordion 16 between the inlet and outlet members and rocker structure 17 for positioning the outlet end of the spout.

The turn base mount 14 of the spout is a 65 light casting, flanged downwardly at 13 to fit inside the opening 12 through the terminal plate and upwardly at 18 to receive the downwardly directed inlet end of the fabric accordion and extended outwardly to 70 form a sheave 19 for a rope 20 used for the angular regulation of the position of the turn base.

The turn base 14 also carries inwardly 75 extending spokes 21 which support a vertically bored central boss 22 for carrying and guiding a valve 23 at the inlet of the turn base.

The valve 23 controls the rate of discharge 80 of air through the spout and thereby the force with which the parachute is impelled laterally during its descent.

When the valve 23 is closed the descent is merely that due to gravity as modified by 85 natural air currents, and air resistance.

The valve 23 is carried on a central upwardly extending stem 24 which passes through and is guided by the central boss 22, the valve being spring pressed upwardly, toward closure at 25 and carrying a rope or 90 the like 26 that extends downwardly to the operator.

The rope 26 is pulled downward to open the valve whenever it is desired to use the discharge through the spout to effect a lateral movement of the parachute. 95

The discharge spout is made collapsible like an accordion, the outlet ring 15 which is at the extreme outlet of the spout being positioned by the rocker structure 17 which 100

has pivot support at 27 upon the outer end of a bracket 28 from the turn base and carries the ring 15 at its upper end, the connection at 29 between the ring and rocker structure optionally being a rigid one in order to secure a definite angular positioning of the ring when the rocker is in its raised position.

The rocker 17 desirably comprises spaced radius rods connected by fabric that is desirably reinforced with suitable wiring 30. In collapsing position of the spout the rocker lies flat against the turn base 14.

During descent of the parachute the spout will normally occupy its collapsed position until or unless the valve 23 at the inlet of the spout has been opened after which the air escaping upwardly from under the parachute to find outlet through the spout raises the spout to the position shown in the figures, the rocker 17 then being vertical and the discharge being horizontal with a resultant reaction tending to impel the parachute laterally in a direction opposite to that of the air discharge.

I preferably provide roller bearing connection between the terminal plate 7 and the turn base 14, illustrating the central flange of the terminal plate as being formed with a runway at 31 and an outwardly extending flange 32 with which I have provided a suitable bolt and gib connection 33 with the turn base, this connection permitting rotation of the turn base with respect to the terminal plate but preventing any longitudinal movement of one plate with respect to the other in a direction longitudinal of the axis of rotation, that is preventing longitudinal separation of the turn base from the terminal plate.

In operation a user during descent, steers the parachute laterally by the ropes 26 and 20, pulling on the rope 26 to open the discharge valve 23 and then suitably adjusting the angular direction of discharge by pulling on the rope 20, controlling the force with which the parachute is impelled by varying the opening of the valve 23.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In a parachute, a body for preventing rapid descent, an air spout having a vertical inlet from below the body and a lateral outlet above the body and means for angularly regulating the direction of outlet of the spout with respect to the body.

2. In a parachute, a body for preventing rapid descent having an opening for upward air discharge, an air discharge spout including inlet and outlet terminals and an intermediate collapsible accordion, the inlet terminal comprising a turn base around the opening, a lateral bracket on the turn base, a radius support for the outlet terminal positioning the outlet along an arcuate path and having a pivot on the bracket and means for adjusting the angular position of the turn base.

3. In a parachute, a body for preventing rapid descent, an air spout having a vertical inlet from below the body and a lateral outlet above the body, a valve controlling the passage of air through the spout and means for angularly regulating the direction of outlet of the spout with respect to the body.

4. A parachute, walls forming an air outlet therefrom directed at an angle to the axis of the chute, a mounting for the walls permitting them to turn with respect to the chute and means for effecting a turning movement of the outlet to direct a descent of the parachute.

5. A parachute having an outlet, a valve and valve-control therefor to determine the extent of flow through the outlet, walls directing the outlet air at an angle to the axis of the parachute and turning means for altering the direction of the outlet with respect to the body of the parachute.

6. A parachute, a controllable outlet for air from the upper part of the parachute, walls for altering the direction of the discharge from the outlet with respect to the axis of the parachute, the walls being collapsible for folding and turning means within the reach of the parachute operator for revolvably altering the direction of the outlet.

7. A parachute body having an opening at its approximate center, a bellows outlet therefrom discharging at an angle to the axis of the parachute, a circular mount for the bellows adapting it to be turned with respect to the body of the chute and a cord and pulley connection with the bellows moving it in the mount.

8. A parachute body having an opening at its approximate center, a bellows outlet therefrom discharging at an angle to the axis of the parachute, a circular mount for the bellows adapting it to be turned with respect to the body of the chute, a cord and pulley connection with the bellows moving it in the mount and valve means for controlling the amount of outlet air passing through the bellows.

9. A parachute body, a central opening, a tube outlet therefrom discharging at an angle with the vertical axis of the parachute and a valve in said discharge.

10. A parachute having a central opening,

an angular discharge pipe therefrom adapted to collapse upon the chute about the opening, means for controlling outlet through the discharge pipe and means for altering the direction of the outlet with respect to the body of the chute operable from the seat of the parachute.

ALBERT A. LONGAKER.
